UNITED STATES PATENT OFFICE.

JACOB P. WRIGHT, OF NEW HAVEN, ASSIGNOR TO THE DIAMOND MATCH COMPANY, OF WESTVILLE, CONNECTICUT.

PLANER-CHUCK.

SPECIFICATION forming part of Letters Patent No. 286,362, dated October 9, 1883.

Application filed May 4, 1883. (Model.)

To all whom it may concern:

Be it known that I, JACOB P. WRIGHT, of New Haven, county of New Haven, and State of Connecticut, have invented new and useful

5 Improvements in Planer-Chucks; and I do hereby declare that the following is a full and exact description of the same, reference being had to the accompanying drawings, and to the letters of reference marked thereon.

10 This invention relates to that class of chucks the members of which are specially adapted for use in connection with planers and other similar machines; and it consists, mainly, first, in the combination of the movable jaw of the chuck and a certain holding-bar and holding-bolts with a tapering locking-key; and, second, in the combination, with the movable jaw, of an auxiliary holding-block of special construction, as will be fully described hereinafter.

15 In the drawings, Figure 1 represents a perspective view of my improved chuck; Fig. 2, a vertical sectional view of the movable jaw, some of the parts of the same also being shown detached; Fig. 3, a transverse sectional view of the movable jaw and the auxiliary holding-block; Fig. 4, a plan view of the base-piece of the chuck detached; Fig. 5, a plan view of the movable portion B reversed; Fig. 6, a central vertical sectional view of the base-piece A and movable portion B.

20 To enable others skilled in the art to make my invention; I will proceed to describe fully the construction of the same.

25 A, Figs. 1 and 4, represents the base or foundation piece of the chuck, consisting of the circular plate a, having the projecting ears a' a', with slots adapted to receive the bolts which secure the base-piece to the planer-table in the manner well understood.

30 a' a', Fig. 4, represent segmental recesses in the inner face of the plate, which are provided with overhanging edges, as shown.

35 a' represents a square opening formed in the plate a at one end of each recess, as shown.

40 a', Figs. 4 and 6, represents a central circular projection formed upon the inner face of the plate, as shown.

45 B, Figs. 1, 2, and 6, represents that portion 50 of the chuck which carries the jaws for holding the work, consisting of a circular plate, b, with

central circular recess, b', adapted to receive the central circular projection, a', of the base-piece, and the holes b² b², for receiving the bolts C C, hereinafter referred to.

55

b³ represents a quadrangular plate, rigidly secured to the outer face of the plate b, either by being cast thereon or being otherwise attached thereto, which plate b³ is provided upon each side with narrow slots b⁴ b⁴, below which, and communicating therewith, are wider grooves in the portion b, as shown in Figs. 2 and 6.

b⁵ represents a series of vertical holes located near the edge of the plate b, which holes open below into a space formed by cutting away the corners of the plate, as shown. The purpose of this construction is to permit anything falling into the holes to be readily discharged.

b⁶, Fig. 1, represents a block projecting from one end of the plate b³, which forms the fixed jaw of the chuck, as will be hereinafter described.

C C represent bolts, the heads of which are held in the segmental recesses a² a² of the base-piece A in such manner as to move freely therein within the limits of the recesses. These bolts extend through the holes b² b² of the plate b, and are provided with nuts, as shown. By means of this construction the plate b is secured to the plate a in such manner as to be capable of making a partial rotation thereon, the engagement of the projection a' with the recess b' serving to guide the parts properly in their movement.

75

D represents the movable jaw, consisting of a block having the bearing-face d, Fig. 2, the vertical openings d' d', Fig. 6, for holding the bolts, hereinafter referred to, the longitudinal slot d², Figs. 1 and 2, with inclined base, as shown in Fig. 6, and the overhanging portion d', Fig. 2, as shown.

80

E E represent bolts, the heads of which are adapted to be held in the slots b⁴ b⁴ of the plate, b, and the shanks of which extend up through the movable jaw, as shown.

85

e, Fig. 2, represents a vertical slot in the upper end of each of the bolts, and F a bar having recesses f f, which bar is adapted to hold the upper ends of the bolts, as shown.

90

G represents a key-bar of wedge or tapering form, which is adapted to be inserted in

95

100

the longitudinal slot of the movable jaw between the inclined base of the same and the lower side of the holding-bar. By moving this key-bar longitudinally in the slot in the proper direction the heads of the bolts E E will be tightly drawn against the overhanging portions of the slots of the plate b, and thus be caused to lock the movable jaw to the plate b. By means of the headed bolts E E the movable jaw, when the locking-key is withdrawn, or partially withdrawn, may be moved into any desired position relatively to the fixed jaw, and then be locked in that position, in the manner before described.

15 H represents an auxiliary holding-block, provided with a horizontal projection, h, having an inclined surface, and a vertical projection, h', having the adjusting-screws h² h², as shown.

20 h³, Fig. 3, represents a pin projecting from the lower face of the block, one being located at each end, which pins are adapted to enter any pair of the series of holes in the plate b. By means of this construction the auxiliary holding-block is adapted, by means of its adjusting-screws, to press upon the upper portion of the movable jaw and move the upper edge of the same forward slightly, to clamp more strongly the work which is being held.

25 30 The general operation is substantially as follows: The base-piece a of the chuck is secured to the head or bed of the planer or other machine with which it is desired to use the same by means of bolts extending through the slots in the ears a' a', in the manner well understood. The plate b, by means of the bolts C C and the segmental recesses a² a² in the base-piece, may be rotated within certain limits for the purpose of bringing the jaws of the chuck 35 into any desired position. When adjusted the parts may be rigidly secured together by screwing up the nuts c c. The work to be held having been laid upon the chuck with one side bearing against the fixed jaw, the movable 40 jaw is moved against the other side of the work, and securely locked in that position by thrusting the tapering locking-key G into its proper position in the longitudinal slot d².

The auxiliary holder H is also adjusted upon the plate b with the movable jaw, and when the latter is locked the adjusting-screws of the former are turned to cause the upper edge of the jaw to clamp more tightly the upper edge of the work which is being held.

50 The movable jaw and the auxiliary holder 55 can readily be removed from the plate b when desired.

Some of the advantages of the described construction are as follows: The construction of the parts for locking and holding the movable jaw is quite simple, and yet the action is effective and the operation of locking can be readily and easily performed. The auxiliary holding-block furnishes a useful adjunct for increasing the clamping action.

65 Having thus fully described my invention, what I claim as new, and desire to secure by Letters Patent, is—

1. The combination of the movable jaw of the chuck and the holding-bar and holding-bolts, with a tapering locking-key, substantially as described.

70 2. In combination with the fixed jaw b⁶, the movable jaw D, with slot d², having the inclined base, bolts E E, holding-bar F, and tapering locking-key G, as and for the purpose described.

75 3. In combination with the movable jaw D, the auxiliary holding-block H, with horizontal projection h, having an inclined surface, as and for the purpose described.

80 4. The chuck described, having the base-piece a, with ears a' a', segmental recesses a² a², and central circular projection a⁴, the plate b, with recess b', plate b³, slots b⁴ b⁴, series of vertical openings b⁵ b⁵, and fixed jaw b⁶, the bolts C C, the movable jaw D, with slot d², bolts E, holding-bar F, and key G, and the auxiliary holding-block H, with adjusting-screws h² h² and pins h³ h³, all combined and 85 arranged as and for the purpose described.

90 J. P. WRIGHT.
